UNITED STATES PATENT OFFICE

2,152,486

CONTROL AND ILLUMINATING OF REFRIGERATOR CABINETS

James L. Knight, Erie, Pa., assignor to General Electric Company, a corporation of New York

Application November 3, 1936, Serial No. 108,955

4 Claims. (Cl. 236—1)

My invention relates to refrigerator cabinets, and particularly to an arrangement associated with the refrigerated compartment of such a cabinet for illuminating the interior of the compartment and preventing undesirably low temperatures therein.

In household refrigerators a source of illumination is usually placed within the refrigerated compartment which is controlled by the operation 10 of the door so that the source of illumination is turned on when the door is opened and turned off when the door is closed. It is desirable that such articles, as fruits, vegetables, meats, and other perishables placed in the refrigerated compartment be kept at a low temperature near freezing to properly preserve these articles; yet such articles must not be permitted to freeze. Upon the occurrence of low room temperatures the refrigerating apparatus associated with the 20 refrigerated compartment will freeze the contents thereof due to the diminished heat leakage into the refrigerated compartment at these low room temperatures. Moreover, if the room temperature goes below freezing the contents of the refrigerated compartment will be frozen whether 25 or not the refrigerating apparatus is operated.

Accordingly, it is an object of my invention to provide an improved arrangement for illuminating the interior of a refrigerated compartment 30 and for preventing undesirably low temperatures therein. I accomplish this by providing an arrangement responsive to the temperature within the refrigerated compartment for turning on the door controlled source of illumination upon the occurrence of undesirably low temperature in the refrigerated compartment, and thus supply sufficient heat from the source of illumination under this condition to prevent the contents of the refrigerated compartment from being frozen.

Further objects and advantages of my invention 40 will become apparent as the following description proceeds, and the features of novelty which characterize my invention will be pointed out with particularity in the claims annexed to and forming a part of this specification.

For a better understanding of my invention reference may be had to the accompanying drawing, in which Fig. 1 is a perspective view of a refrigerator cabinet embodying my invention; 50 and Fig. 2 is an enlarged fragmentary view, partly in section, of a portion of the refrigerator cabinet, shown in Fig. 1, and an electrical diagram of the circuits employed.

Referring to the drawing, in Fig. 1 I have shown 55 a household refrigerator cabinet 10 provided with

an insulated refrigerated compartment 11 having an opening 12 in one wall thereof and a door 13. A refrigerant evaporator 14 is housed in the compartment 11 to refrigerate the same and is connected to a suitable source of refrigerant such 5 as a compressing and condensing unit 15 arranged on top of the cabinet. An electric lamp 16 is mounted within the refrigerated compartment in such position that it will illuminate the interior of the compartment when the circuit in 10 which it is included is completed to a source of supply. An electric switch 17 is mounted in the opening 12 in the refrigerator cabinet in such position that it will be actuated by the door 13 to close the switch when the door is opened and 15 to open the switch when the door is closed. Also a thermostatic switch 18 is positioned in the refrigerated compartment in contact with the cold air circulated therein. This thermostatic switch is positioned on the lower right hand portion of the rear wall of the refrigerated compartment so as to be responsive to the average 20 temperature prevailing in the refrigerated compartment and not to be unduly affected by the low temperature of the surface of the evaporator 25 14.

Referring now to Fig. 2, it will be seen that the electric circuit above referred to comprises conductors 20 connected to a suitable source of supply, the electric lamp 16 and two parallel 30 branch circuits 21 and 22. The branch circuit 22 includes the door operated switch 17. An electric circuit may be established from the source of supply through the lamp 16, either through the branch circuit 21, including the thermostatic 35 switch 18, or through the branch circuit 22, including the door operated switch 17. The lamp may thus be energized by operation of either switch independently of the other.

The door operated switch 17 is preferably of 40 the plunger type and, as illustrated, comprises a plunger 30 spring biased to an outward position, a bridging contact member 31 secured to the plunger 30, and a plurality of cooperating stationary contacts included in the branch circuit 45 22. The contact members of the switch are housed by a suitable moisture proof housing 32, such as hard rubber or the like, to prevent any moisture present in the surrounding thermal insulating material 33, between the inner and outer 50 metallic walls 34 and 35, respectively, of the insulated compartment, from corroding the contact members. The door operated switch 17 is normally biased to an outward or closed position and is actuated to an open position by the engage- 55

ment of the door 13 with the plunger 30, when the door is closed. Hence, the switch 17 closes the branch circuit 22 when the door 13 is opened, and opens the branch circuit 22 when the door 13 is closed. In this manner the lamp 16 is turned on when the door is opened and normally turned off when the door is closed.

The thermostatic switch 18 may be of any suitable type. The switch illustrated comprises a movable contact 40 carried on the free end of a bimetallic element 41, which is secured at the other end thereof to a fixed support 42. The contact 40 is arranged in operative relationship with an adjustable stationary contact 43. When the temperature of the bimetallic element 41 is above a predetermined temperature the contacts 40 and 43 are retained in an open position and the branch circuit 21 is broken. When the temperature of the bimetallic element 41 is below a predetermined low temperature, the contacts 40 and 43 are retained in a closed position and the branch circuit 21 is completed. Thus, the thermostatic switch 18 normally opens and closes the branch circuit 21 as the temperature within the cabinet 11 rises above and falls below predetermined temperatures.

In operation of the circuit, when the door 13 is opened a circuit is completed from the source of supply through the lamp 16 by way of the branch circuit 22 and the switch 17. This illuminates the interior of the cabinet. When the door is closed the branch circuit 22 is broken by the switch 17, and the lamp 16 is turned off. During the operation of the refrigerator, if the temperature within the refrigerated compartment 11 falls below a predetermined low temperature within the freezing range due, for example, to a change in outside temperature, the thermostatic switch 18 closes the branch circuit 21, thus completing a circuit through the lamp 16 from the source of supply and the lamp 16 supplies heat to the compartment to prevent freezing of articles therein. When sufficient heat has been added to the compartment 11 to cause the temperature therein to rise to a predetermined temperature above freezing, the thermostatic switch 18 breaks the branch circuit 21 and turns off the lamp 16. Thus, the lamp and thermostatic switch associated therewith prevent the contents of the refrigerated compartment from being frozen.

Although I have shown a particular embodiment of my invention, I do not desire my invention to be limited thereto, and I intend in the appended claims to cover all modifications within the spirit and scope of my invention.

What I claim as new and desire to secure by Letters Patent of the United States is:

1. A refrigerated compartment provided with a door, an electric lamp arranged to illuminate and to heat said compartment, an electric circuit for said lamp, illumination control means including a switch in said circuit for closing said circuit in response to opening said door and for opening said circuit in response to closing said door, and heat control means including a thermostatic device responsive to the temperature within said compartment for independently controlling said circuit.

2. A refrigerated compartment provided with a door, an electric lamp arranged to illuminate and to heat said compartment, an electric circuit for said lamp, illumination control means including a switch in said circuit for closing said circuit in response to opening said door and for opening said circuit in response to closing said door, and heat control means including a thermostatic device positioned in said compartment and responsive to the temperature of the air therein for independently controlling said circuit.

3. A refrigerated compartment provided with a door, an electric lamp arranged to illuminate and to heat said compartment, an electric circuit for said lamp, illumination control means including a switch in said circuit for closing said circuit in response to opening said door and for opening said circuit in response to closing said door, and heat control means including a thermostatic device in said circuit and responsive to the temperature within said compartment for closing said circuit when the temperature in said compartment falls to a predetermined low temperature and for opening said circuit when the temperature in said compartment rises to a predetermined higher temperature.

4. A refrigerated compartment provided with an opening therein, a door for closing said opening, an electric lamp mounted within said compartment and arranged to illuminate and to heat the same, an electric circuit for said lamp, means including a switch in said circuit and positioned in said opening for controlling the illumination of said compartment, said switch being actuated to close said circuit when said door is opened and actuated to open said circuit when said door is closed, and heat control means including a thermostatic device in said circuit and positioned in said compartment to be subject to the cold air circulated therein for closing said circuit when the temperature in said compartment falls to a predetermined temperature near freezing and for opening said circuit when the temperature in said compartment rises to a predetermined temperature above freezing.

JAMES L. KNIGHT.
